UNITED STATES PATENT OFFICE

LOTHAR R. ZIFFERER, OF COLUMBIA, PENNSYLVANIA; MABEL C. ZIFFERER, HARRY E. CHAMPION, AND H. NELSON ALBRIGHT, EXECUTORS OF SAID LOTHAR R. ZIFFERER, DECEASED, ASSIGNEES TO UTILATREE PRODUCTS INC., OF NEW YORK, N. Y., A CORPORATION OF PENNSYLVANIA

COSTUMER

Application filed October 6, 1930. Serial No. 486,612.

This invention relates to a costumer having capacity for the support of a large number of hangers together with such articles of clothing as may be suspended therefrom. It is designed to be set up for continuous or intermittent use, and to be taken apart and folded up when withdrawn from service. A costumer having these characteristics is especially desirable for the accommodation of coats and wraps on the occasion of gatherings, ceremonies, parties, etc., at both public and private places.

The improvements characterizing this invention have to do with features which lend strength and stability to a costumer of the knock-down type, ready adaptability of certain foldable components for the support of headware or footwear articles; and facility in the setting up or taking down of the costumer when it is to be placed in use or put away. Objects, such as these, as well as others which are hereinafter set forth, are attained by my invention, a suggestive embodiment of which is set forth in the accompanying drawings in the manner following:

Figure 1 is a side elevation of the costumer in its entirety;

Fig. 2 is a similar view of the costumer top unit with the parts collapsed or folded upon each other;

Fig. 3 is a detail in enlarged vertical section showing the cap assembly at the upper extremity of the costumer;

Fig. 4 is a top plan view of the costumer;

Fig. 5 is a detail in vertical section showing the connection between the head and supporting bars;

Fig. 6 is a detail in section on line 6 of Fig. 5;

Fig. 7 is a detail in vertical section showing one form of connection between the top and bottom units of the costumer; and

Fig. 8 is a vertical sectional view through a supporting bar of modified construction.

The costumer herein shown utilizes a tubular vertical stand composed of two (or more) connected sections 9 and 10 forming top and bottom units respectively. Fitted partly within the connecting end of one section, as 50 9, is a sleeve 11 locked in place as by a cross

pin 12 (see Fig. 7). A shoulder 13 extended laterally from the sleeve overlies the proximate end of the tubular section wherein the sleeve is secured. The remaining portion of the sleeve extends beyond the tube end for fitting within the other tubular section, as 55 10. I provide a non-rotatable connection between the sleeve and latter tube and this may consist of a pin or screw 14 anchored in the sleeve having its projecting end lying 60 within an elongated slot 15 which opens out at the end of the tubular section 10. This construction, most clearly shown in Fig. 7, is suggestive of one which will meet the purposes of my invention.

The bottom unit of the costumer is provided with a supporting base of some sort, preferably one of a folding or collapsible character, as shown in Fig. 1. This may take the form of three folding legs 16, each having its upper end pivoted at 17 to a collar 18 which is slidably fitted on to the lower tubular section of the stand. This collar may be locked in either its upper or lower extreme position as by means of a set-screw 19. The 70 lower position may be determined by a stop 20. Link connections 21 extend from a collar 22 having a fixed mounting adjacent the bottom end of the stand to a point intermediate of each leg to which they are pivotally joined as at 23. By providing a slot 24 extending from each pivotal connection 23 close to the lower end of the leg, the several links may be accommodated within the legs when the latter are folded to a position parallel with the stand. In executing this movement the lock 19 is in released position permitting the collar 18 to slide upwardly as far as necessary for this purpose.

The construction of the lower stand unit 90 may be variously modified, it being desirable from the standpoint of my invention that it provide a base support which will maintain the stand erect regardless of the distribution 95 of the load which is carried near its upper end; and that the joined sections of the stand be interlocked against relative rotation. The construction just described is advantageous in the particulars noted, and also in that it is 100 of a foldable character permitting the legs to

lie alongside of the stand whereby a minimum of space is required for its storage.

The tubular section forming the upper stand unit supports at its top a head 30 from which is upwardly extended a rod 31 which is preferably of reduced diameter and screw-threaded at its upper end to support thereon a bell-shaped cap 32. A shoulder 33 is formed at the lower end of this threaded extremity with which is engaged, by a screw-threaded connection, a hub 34 which is provided interiorly of the cap for bearing down upon the shoulder. This hub also extends laterally beyond the shoulder to provide a stop, as will be presently pointed out. A lock nut 35 may be applied over the end of the rod in screw-threaded relation therewith, and I may associate with this nut a plate 36 carrying any desired ornamentation.

Slidably mounted on the rod is a collar 40 to which are pivotally joined as at 41 a plurality of arms 42 each adapted to extend through an opening 43 in the cap. The free end of each arm may be laterally turned to carry a knob 44. The arms when extended outwardly as shown in Figs. 1 and 3 provide supports for hats and other like articles. In this position of distension, the arms tend to remain due to their outer ends overbalancing the weight of the collar 40 to which they are joined. Due to the collar striking against the end of the hub 34 which acts as a stop therefor, the lateral position of the arms is definitely fixed. If the latter be pulled downwardly, however, as shown in Fig. 2, the arms will be drawn in to lie substantially parallel with each other and the rod 31, the knobs 44 then resting upon the exterior of the cap to limit the downward movement of the collar.

The rack just described may be variously positioned or duplicated on the costumer stand, as indicated plainly in Fig. 1. A second rack of like construction and characteristics is shown as arranged in a lower position where it may serve admirably as a support for footwear. Obviously the location or number of such racks having folding arms as described is a matter of choice with the designer.

The head 30 is formed with a shouldered body 50 which is fitted within the upper end of the upper tubular section 9 where it may be locked in place as by a cross pin 51 (see Fig. 5). Extending oppositely from the body are shoulders 52, each in the form of an arch or inverted U with depending sides 53. Open slots 54 extend inwardly from opposite ends of the shoulders along their tops for a purpose which will presently appear. Slidably mounted upon the upper tubular section of the stand is a collar 55 from which extend opposite lugs 56 the upper portions of which are received within slots 57 of plugs 58 immovably mounted adjacent the inner

ends of two supporting bars 59. These bars which may be of tubular formation are adapted in one position to present their inner ends between the sides 53 of the arched shoulders 52 where they may be held by a set-screw 60 which is carried by the collar 55. Fitted immovably within the outer end of each arm is a second plug 61 having a lateral ear 62 (see Fig. 8) with which is pivotally connected, at 63, a link 64 having its opposite end joined pivotally with the cap 32, as at 65. The two links cooperate with the outer bar ends to support the same laterally and in alignment with each other, as shown best in Fig. 1. By reference to Fig. 8, it will be noted that the ear 62 of each plug is extended upwardly through a slot 66 adjacent the bar end whereby to engage with the slot end in providing support for the bar when a load, considerable or otherwise, is sustained thereby.

The construction herein described is such that the two supporting bars 59 may be collapsed or folded relative to the stand by a downward pull of the collar 55. The parts will then be related as shown in Fig. 2. When re-positioned in the relationship indicated in Fig. 1, the two bars will be aligned horizontally on opposite sides of the stand so as to provide a support from which a plurality of hangers 67 may be slidably depended.

There are several features embodied in the present construction which contribute measurably to its strength, stability, etc. Among such points I would have it noted that the two supporting bars which are adapted to extend oppositely from the stand, are aligned with two of the bearing points of the base. This is illustrated in Fig. 4 where I have shown most clearly the three point base support formed by the legs 16. The bars are aligned with two of such points to receive the benefit of the maximum spread of the parts forming the base. This is of importance because the load, sustained by the two hanger bars, is ordinarily never perfectly balanced, thereby setting up a tendency for the entire stand to topple in the direction of that bar which is most heavily loaded. Any such deviation from the vertical is resisted most effectively by aligning the hanger bars with two of the bearing points of the base, as already pointed out.

This positioning of the hanger bars relative to a multiple point base support is assured by the provision of such parts as are embodied in the structure described. For instance, the head 30 is pin-locked to the upper tubular section 9 so as to maintain the two arched shoulders 52 always in a definitely fixed position relative thereto, thereby guiding and holding the hanger bars in the same fixed position when they are swung into horizontal position, as shown in Figs. 1 and 5.

Also the upper and lower tubular sections of the stand are locked in a fixed rotative relationship as by the pin 14 in cooperation with the slot 15, thereby assuring a disposition of the legs at the base in accordance with the 5 plan already explained.

There is also built into the costumer an amplitude of strength for the support of the two hanger bars each of which forms the base 10 of a triangle whose other two sides are the associated link 64 and the common central rod 31. Inasmuch as each bar is prevented by the shoulder from swinging upwardly past the horizontal, any load carried by one 15 bar alone is sustained by its associated link in connection with the central rod and the other link and bar, and vice versa. The connection of each link with the outer end of the associated bar forms also a stop beyond which 20 hangers may not slide in response to the pressure of numerous wraps which may be hung on the costumer. It is, therefore, possible to load the two bars to capacity without risk of any kind. The hangers of which a number 25 are shown in Fig. 1 may occupy variable positions throughout the length of each bar, and, in fact, may even be depended from the arched shoulders adjacent the rod due to their size and curvature conforming closely to 30 that of the bars.

The hangers used may be of the conventional type with upwardly extending hooks fitting loosely over the supporting bars, or they may be specially formed in case of a modification 35 in the bar construction as suggested, for example, in Fig. 8. Here the bar is provided on its under side with an elongated slot 70 enlarged at 71 adjacent its inner end, and cooperating therewith is a stem 72 having at 40 its upper end a head 73 adapted to pass through the slot enlargement but not elsewhere. This stem is upwardly extended from a hanger (not shown) to support the same from the bar 59. In this construction the 45 several hangers may slide, as required, lengthwise of the bar to which they remain connected except when pulled back to the starting point at the enlarged end of the slot.

A costumer embodying the features of improvement herein described is sturdy to a 50 degree which will meet all requirements of occasional or continuous service. Due to the cantilever mounting of the hanger bars with supporting tension links connecting with the stand at a higher point, it is possible to leave 55 clear below the bars a maximum of space for accommodation of garments or wraps. The load which such hanger bars are capable of sustaining is very considerable, so much so 60 that little attention need be given this point or the manner in which the load is distributed upon the bars.

I claim:

1. A costumer in which is combined a vertical stand whereon is slidably mounted a collar

to which are pivotally joined the inner ends of a pair of bars, link connections between the outer bar ends and the stand at a point remote from the collar whereby the bars may be swung into horizontal position upon opposite 70 sides of the stand, and a stop for the collar carried by the stand extending laterally from opposite sides thereof and arched to overlie the proximate ends of the bars when the latter are in horizontal position, the stop being conformed closely to the associated bar ends 75 whereby the upper surfaces thereof may serve as hanger extensions therefor.

2. A costumer in which is combined a stand having a hollow cantilever bar with its under side slotted for the major portion of its length and terminating in an enlargement near one end of the bar, and a hanger having an upwardly projecting sustaining stem terminating in an enlargement of a size small enough 80 to enter the enlarged end of the bar slot but big enough to be prevented from passing through the slot elsewhere, the hanger so interlocked with the bar being adjustable for the length of the slot and detachable therefrom only when moved to one extreme position therein.

3. A costumer in which is combined a stand having a freely slideable collar furnishing pivotal support for the inner ends of two cantilever hanger bars the outer ends of which are connected to the stand by tension means, and a combined stop and rotative lock associated with the collar against which the inner bar ends are engaged to maintain them positively 95 in alignment in a fixed rotative position relative to the costumer.

4. A costumer having a sectional stand with means for preventing relative rotation between the sections, a base supporting the lower section non-rotatably, a head carried on the top section having oppositely extending guides, a collar slideable on the stand to a position adjacent the head, a pair of hanger bars pivoted to the collar and maintained by the head guides in alignment with each other on opposite sides of the stand and in fixed rotative position relative thereto, and cantilever supporting connections for the bars.

5. A costumer having a base supporting a stand on which is carried a cantilever hanger bar with tension means pivotally connecting the outer end thereof to the stand, a collar pivotally connected to the inner bar end and mounted for sliding movement on the stand, a combined stop and guide for the bar affixed to the stand, and locking means carried by the collar for securing the bar in collapsed or extended positions.

6. A costumer in which is comprised a base supporting a stand on which is carried a hollow cantilever bar with plugs secured to each end thereof, a tension means forming a cantilever connection between the plug at the outer bar end and a higher point on the support, a 125

- collar slidable on the stand having a pivotal connection with the plug at the inner bar end, and means for securing the collar in a selected position whereby to determine the angular position of the hanger bar relative to the stand.
7. A costumer having a stand to which is affixed a slotted supporting cap, a collar slidable on the stand toward and from the cap, a rack arm pivoted to the collar extended loosely through the cap slot and slidably supported thereby either relatively vertically or horizontally, the arm portion extended beyond the cap, when horizontally disposed overbalancing the remaining portion within the cap connected to the collar, and a cantilever bar extended laterally from the stand at a point below the collar having a connection through tension means with the cap.
8. A costumer having a stand to which is affixed a slotted supporting cap, a collar slidable on the stand toward and from the cap, and a rack arm having at one end a head and pivoted at the other to the collar for loose extension through the cap slot and slidably supported thereby either relatively vertically or horizontally, the arm head being engageable with the cap to serve as a stop for movement of the collar away therefrom when the arm is swung to vertical position.
9. A costumer having a stand from which is laterally extended a cantilever bar, a slotted cap near the top of the stand, tension means extending between the cap and bar ends, a collar slidable on the stand between the bar and cap, and a plurality of rack arms pivoted to the collar and extended past the tension means through the cap to derive therefrom a sliding support through various angular positions which depend upon vertical adjustment of the collar.
